(57) **CLAIM**

The ornamental design for game table display rack, as shown and described.

DESCRIPTION

FIG. 1 is a perspective view of a game table display rack, with a game table and signs shown in broken lines for illustrative purposes only and forming no part of the claimed design, showing our new design.

FIG. 2 is an enlarged perspective view of the game table display rack.

FIG. 3 is a front view thereof.

FIG. 4 is a side view thereof, the other side being a mirror image thereof.

FIG. 5 is a top view thereof.

FIG. 6 is a bottom view thereof; and,

FIG. 7 is a rear view thereof.
